UNITED STATES PATENT OFFICE.

EDITH HANKS OF DENISON, TEXAS, ASSIGNOR OF ONE-HALF TO
GEORGE B. ANDERSON, OF DENISON, TEXAS.

CHILD'S GARMENT.

No. 839,139.

Specification of Letters Patent.

Patented Dec. 25, 1906.

Application filed July 27, 1905. Serial No. 271,443.

To all whom it may concern:

Be it known that I, EDITH HANKS, a citizen of the United States, residing at Denison, in the county of Grayson and State of Texas, have invented a new and useful Child's Garment, of which the following is a specification.

This invention relates to children's garments.

The object of the invention is to provide a garment which may be worn either as an outdoor covering, or as a night-wrapper and which will permit free use of the limbs, ready access to the underwear, if desired, and which may be worn by children of either sex with perfect comfort and ease.

With the above and other objects in view, as will appear as the nature of the invention is better understood, the same consists in the novel construction and combination of parts of a child's garment, as will be hereinafter fully described and claimed.

In the accompanying drawings, forming a part of this specification, and in which like characters of reference indicate corresponding parts, Figure 1 is a view in elevation of the garment spread out flat and viewed from the front. Fig. 2 is a view in rear elevation, showing the garment as it appears when on the wearer. Fig. 3 is a similar view showing the lower parts of the garment unfastened to permit access to the underclothing. Fig. 4 is a fragmentary detail view of the lower portion of the garment viewed from the rear.

The garment embodies a body portion 1, which, as shown in Fig. 1, may be constructed of two parts 2 and 3 connected at the front by the seam 4. While this will generally be the preferred manner of constructing the garment, it will be understood that the garment may be made of a single piece of material and still be within the scope of the invention. The body portion is so cut that the garment when its parts are assembled for wear has the appearance of an ordinary pair night-drawers, with the exception that the legs are shortened to permit free movement of the legs of the wearer, a feature that is essential with such garments.

The upper portion of the garment has combined with it a pair of arms 5 of the usual or any preferred construction, and a collar 6, that is slit at the front and the back to avoid any binding around the neck and shoulders.

and also to render the garment cooler in use. There is also combined with the body a belt 55 7, which is held in position by a pair of straps or loops 8, secured to the front of the garment.

The back is split from the top to the bottom, and one flap thus formed is provided throughout a greater portion of its length with buttonholes 9, that are designed to be engaged by buttons 10 on the opposite flap. From the lowest of the buttons 10 the opposed edges of the flaps are cut away, forming an inverted-V-shaped gore 11, Fig. 4, adjacent to the edges of which are secured buttons 12 and 12^a. The bottom portion of the front of the garment has a semicircular piece cut from it, and to the edges of the gore thus formed is secured a crotch-flap 13, at the crest of which is secured a cod-piece 14, there being an opening 15 provided at the top of the crotch-flap, which is normally covered by the cod-piece. The crotch-flap has combined with it a button 16, that is designed to engage a buttonhole 17 on the cod-piece to cause the latter positively to cover the opening 15. The crotch-flap is provided with three buttonholes 18, that are designed to be engaged, respectively, by the lower button 10 and the two buttons 12, thereby effecting a complete closing of the crotch. The lower edge of the body adjacent to the crotch-opening is provided with two buttonholes 19, that are adapted to be engaged by the buttons 12^a, thereby to form the legs of the garment.

When all of the parts are assembled in the manner described, the garment has the appearance of a pair of ordinary bloomers, such as are worn by children in the summer-time except that provision is made for permitting free access to the undergarments without removing the article, this being accomplished by the provision of the crotch-flap 13, which when loosened from engagement with the buttons 10 and 12 will free the lower part of the garment, and by freeing the buttons 12^a from the buttonholes 19 the whole lower portion of the garment will be free from contact with the body and may be turned upward. This latter will be found of particular value at summer-resorts where it is desired to have children play in water without necessarily wetting their outer garments.

The article as described is simple in con-

struction, durable in use, and will in a practical manner fulfil a long-felt want in the nursery and on the playground.

Having thus described the invention, what 5 is claimed is—

1. A child's garment comprising a coat-like body portion open at the back, means for fastening the edges of said opening together except at the bottom thereof at which 10 point the edges of the back opening are at angles to each other and spaced apart, the front portion of the garment having an opening cut thereinto at the center of the lower portion thereof, a crotch-flap having full edges and secured to the edges of the front opening and adapted to fit snugly between the limbs of the wearer, said flap having an opening therein, means for securing said flap to those 15 portions of the rear edges of the garment which are spaced apart, said flap when closed serving to bisect the lower portion of the garment to form leg-receiving portions, a cod-piece carried by said flap, and means upon 20 said flap for fastening said piece in position to close the opening in the flap.
2. A child's garment comprising a coat-like body portion open down the back, means 25 for fastening the edges of said opening to-

gether except at the bottom thereof at which point the edges of the back opening are at angles to each other and spaced apart, the front portion of the garment having an opening cut thereinto at the center of the lower portion thereof, a crotch-flap having full edges and secured to the edges of the front opening and adapted to fit snugly between the limbs of the wearer, said flap having an opening therein, means for securing said flap to those 30 portions of the rear edges of the garment which are spaced apart, said flap when closed serving to bisect the lower portion of the garment to form leg-receiving portions, a cod-piece carried by said flap, and means upon 35 said flap for fastening said piece in position to close the opening in the flap.

In testimony that I claim the foregoing as my own I have hereto affixed my signature in the presence of two witnesses.

EDITH HANKS.
